UNITED STATES PATENT OFFICE

ARTHUR E. CARTER AND CLARENCE A. JOHNSON, OF SAN BERNARDINO, CALIFORNIA

PERFORATING MACHINE FOR WELL CASINGS

Application filed August 31, 1929. Serial No. 389,840.

This invention relates broadly to perforating machines and has more particular reference to a perforating machine especially adapted for perforating the walls of well casings, the primary object of the invention being to provide a device of this nature, which is capable of disposition in the well casing, and including a plurality of pivotally mounted knives normally maintained in an inoperative position but which, upon the application of force to the device, will be moved to a cutting position for piercing the walls of the casing. A still further object of the invention is to provide a device of this nature, adapted to be suspended in the well casing through the medium of the usual well equipment for this purpose and which may be worked up and down in the casing so that the knives of the device may penetrate the walls of the well casing for perforating the same.

A still further object of the invention is to provide a device of this nature, which is simple in construction, strong, durable, thoroughly reliable, practical and efficient in operation and otherwise well adapted to the purpose designed.

Other objects and advantages of the invention will become apparent during a study of the following description, taken in connection with the accompanying drawings, wherein:

Figure 1 is a side elevation of a well casing perforating machine constructed in accordance with the present invention, and showing the knives in an inoperative position, and the device prior to its insertion in the well.

Figure 2 is a top plan view thereof with the concaved knife backing plate being shown in transverse section.

Figure 3 is a front elevation of a knife backing plate.

Figure 4 is a perspective view of one of the perforating knives.

Figure 5 is an end elevation of one of the perforating knives.

Figure 6 is a detail view, partly in section and partly in elevation of the device when the knives are in a cutting position.

Figure 7 is a transverse detail sectional view, taken substantially on the line 7—7 of Figure 6.

Figure 8 is a fragmentary detail longitudinal sectional view of the lower end of the main handle.

Figure 9 is a top plan view of the spider showing the same in position on the mandrel, the mandrel being shown in section.

With reference more in detail to the drawings, it will be seen that my improved perforating machine for well casings comprises an elongated rod or mandrel 5, which rod or mandrel 5 is preferably square in cross section and at its upper end terminates in the reduced tapered externally threaded end 6, adapted to be threadedly received in a suitable device, whereby the machine may be suspended from a set of jars, which jars form a part of the well equipment and in the art are well known as being standard equipment for such work.

At spaced longitudinal points and inwardly from the ends, the mandrel is provided with the upper stop collar 7 and a lower stop collar 8. An upper spider 9 comprises a rectangular hub 10, through which the upper end of the mandrel 5 extends for slidably supporting said spider on the end of the mandrel, the spider having the arms 11 extending one from each of the four sides of the hub as shown to advantage in Figure 9.

In normal position, the hub 10 of the spider 9 will rest upon the collar 7. A lower spider, designated generally by the reference character 12 has a rectangular hub 13, from the sides of which extend the arms 14, the spider 12 being substantially the same in construction as the spider 9, with the exception that the hub 13 extends beyond the lower edges of the arms 14 as shown to advantage in Figure 6. The upper and lower spiders are connected through the medium of vertical arms or links designated generally by the reference character 15.

There are a plurality of these arms 15 and each of the arms are identical in construction, each arm being formed at its opposite ends with lateral inturned terminals 16—16, and the terminals 16 are provided with a plurality of longitudinally

aligned spaced perforations or openings 17. In practice, a pair of the arms 15 connects an arm 11 of the upper spider with a corresponding arm of the lower spider, and the 5 apertures 17 on the lateral ends 16 of the links or arms 15 are adapted to be selectively registered with an opening 18 formed in the respective arms of the upper and lower spiders, a bolt 19 being passed through the 10 registering apertures 17 and 18 for securing the arms in an adjusted position on the arms of the spider. The length of the arm 15 is greater than the distance between the collars 7 and 8, so that normally when the 15 upper spider is at rest on its collar 7, the lower spider will be positioned downwardly and out of contact of the lower collar 8 or the respective positions of the spider will be such as shown to advantage in Figure 1. 20 Cutting and perforating knives 20 have one end thereof pivoted between a pair of ears 21, which pairs of ears 21 project laterally from each side of the mandrel 5, the pivot pin for the knives being designated as at 22. 25 The outer free ends of the knives 20 are adapted for vertical pivotal movement between the respective pairs of vertical arms or links 15, the outer free end of the knives projecting beyond the arms 15, for movement in the longitudinal slot 23, formed in the respective elongated knife backing plates 24, which plates 24 are of concaved formation in cross section as shown to advantage in Figure 2, and these plates 24 are secured 30 at their upper and lower ends to the arms 11 and 14, respectively, of the upper and lower spiders, the upper and lower vertical edges of the plates being bent inwardly as at 35 against the outer lower and upper edges 40 of the links 15 of the respective pairs of links. The plates 24 have their vertical side edges extending laterally from the adjacent side of the links 15 of the respective pairs as is also shown to advantage in Figure 2. 45 Trip arms 26 are pivoted at their upper ends to the arms 11 of the topmost spider 9, adjacent the hub of the spider, and said trip arms 26 at their lower ends are offset as at 27, the terminals of the offset ends of 50 the arms being pivoted to the respective knives 20.

Normally the arms are in that position shown in Figure 1 or in a non-cutting position and in order to move the arms in a horizontal or cutting position as shown in Figure 6, there is provided a coil spring 27 disposed about the lower end of the mandrel 5, the lower end of the coil spring impinging against a collar 28 threaded on the extreme 55 lower end of the mandrel, and a pin 29 extending through the collar and the mandrel to prevent casual rotation of the collar. The spring 27 is normally in a compressed position and for maintaining the pin in this compressed position a pin 30 preferably of wood

or of some low shearing strength material is inserted in a suitable opening provided therefor in the side of the mandrel 5, a considerable distance beneath the lower end of the collar 8 so as to be below the lower edge of the hub 13 of the lower spider 12 when said spider 12 is at its lowest position as shown to advantage in Figure 1. The operation of our device may be briefly described as follows: The device is normally in the position shown in Figure 1, that is, with the hub of the uppermost spider 9 resting upon the upper collar 7, so that the hub of the lower spider is disposed a suitable distance below the lower collar 8, the spider being in this position. The cutting knives 20 are disposed in the inclined position shown in Figure 1, while the spring 27 is compressed between the collar 28 and the pin or peg 30. At their cutting ends the knives 20 adjacent their upper edges are serrated to provide penetrating or piercing teeth 31, while the lower edge of the knives, at the free ends thereof are suitably sharpened to provide cutting edges as at 32.

Obviously then, the mandrel having its pin 6 threaded in a suitable jarring apparatus, the device with its parts arranged in the position just described, is lowered into the well casing, and the device is lowered into the casing with sufficient force as to forcibly engage the lower end of the mandrel with the bottom of the well one or more times, and the lower end of the mandrel thus repeatedly forced against the bottom of the well will set up sufficient vibration upon spring 27, the same being normally retained in a partially contracted position between collar 28 and the relatively fragile pin 30. Such action will manifestly cause alternate contraction and expansion of the spring with the result that the pin 30 will gradually become weakened and finally sheared thus freeing the spring so that the same upon expansion will abut hub 13, and, at its upper end, the spring thus contacting with sufficient force against the lower end of the hub 13 of the lower spider 12, thus forcing the spider 12 and upper spider 9 upwardly longitudinally of the mandrel, so that the hub 13 will abut the lower collar 8, and this action of the spider will of course draw the trip rod 26 upwardly, thus moving the cutter knives 20 to a substantially horizontal or cutting position with the working edge of the knives extending through the slots of the plates 24, the knives being drawn up with sufficient force as to have their serrated teeth puncture the well casing. Obviously, successive blows from above or a series of jerks will cause an up and down sliding movement of the respective spiders, thus continuously moving the knives about their pivots for pro-

viding a series of openings in the well casing.

Manifestly, when the device is raised out of the well casing, the knives will return to the original position shown in Figure 1 and the operation may be repeated at any desired height within the well casing. It will be necessary to replace pegs on the mandrel only at the beginning of the operation of the device as will be apparent.

The knives 20 are preferably of tool steel temper and the teeth and cutting edge of the knife will permit cutting operation of the knives with a minimum amount of expended energy.

It is believed that from the foregoing description taken in connection with the accompanying drawings, a clear understanding of the operation, construction and advantages of the well casing perforating tool or machine of this character will be had by those sufficiently skilled in this art. A more detailed description thereof is deemed unnecessary.

Even though we have herein shown and described the preferred embodiment of our invention, it is to be understood that the same is susceptible to changes fully comprehended by the spirit of the invention as herein described and the scope of the appended claims.

What is claimed is:

1. In a device of the class described, a mandrel adapted for disposition in a well casing, a spider slidably supported on the mandrel adjacent one end of the mandrel, a second spider slidably supported on the mandrel adjacent the opposite end of the mandrel, means operatively connected to the spiders for maintaining said spiders in a predetermined spaced relation on said mandrel, cutting knives pivoted to the mandrel at the sides of the mandrel intermediate said spiders, trip bars pivoted to the knives and to one of said spiders, a compressible spring convoluted about said mandrel adjacent the lower end thereof, a shearable pin extending transversely through the mandrel and engaging said spring for normally retaining the latter in a compressed condition, and said spring adapted upon expansion thereof to bear against said second spider for urging said spider upwardly longitudinally of the mandrel, whereby said cutting knives are swung vertically about their pivots to a substantially horizontal position for cutting engagement with the wall of a well casing.

2. In a perforating device for well casings, a mandrel adapted for suspension in the well casing, a spider slidably supported on the mandrel adjacent one end of the mandrel, a second spider slidably supported on the mandrel adjacent the other end of said mandrel, vertically disposed arms secured at their ends to the respective spiders for main-

taining said spiders in spaced relation on said mandrels, a plurality of cutting knives, means pivotally connecting said cutting knives to the sides of the mandrel intermediate said spiders, trip arms pivoted to said knives and to one of said spiders, said trip arms adapted to be actuated upon sliding movement of said spiders for moving said arms to a horizontal position for engagement with the well casing, and actuating means engaging the mandrel and one of the spiders for imparting sliding movement to said spiders.

3. In a perforating device for well casings, a mandrel adapted for suspension in the well casing, a spider slidably supported on the mandrel adjacent one end of the mandrel, a second spider slidably supported on the mandrel adjacent the other end of said mandrel, vertically disposed arms secured at their ends to the respective spiders for maintaining said spiders in spaced relation on said mandrels, a plurality of cutting knives, means pivotally connecting said cutting knives to the sides of the mandrel intermediate said spiders, trip arms pivoted to said knives and to one of said spiders, said trip arms adapted to be actuated upon sliding movement of said spiders for moving said arms to a horizontal position for engagement with the well casing, and actuating means for the spiders adjacent one of the spiders for imparting sliding movement to said spiders, said last mentioned means comprising an expansible spring convoluted about the lower end of said mandrel, said spring having one end thereof fixed to said mandrel, and a shearable peg extending transversely through said mandrel and projecting laterally from opposite sides of the mandrel for engagement with the free end of the spring for normally retaining the same in a compressed condition.

4. In a perforating device for well casings, a mandrel adapted for suspension in the well casing, a spider slidably supported on the mandrel adjacent one end of the mandrel, a second spider slidably supported on the mandrel adjacent the other end of said mandrel, vertically disposed arms secured at their ends to the respective spiders for maintaining said spiders in spaced relation on said mandrels, a plurality of cutting knives, means pivotally connecting said cutting knives to the sides of the mandrel intermediate said spiders, trip arms pivoted to said knives and to one of said spiders, said trip arms adapted to be actuated upon sliding movement of said spiders for moving said arms to a horizontal position for engagement with the well casing, and actuating means for the spiders adjacent one of the spiders for imparting sliding movement to said spiders, said last mentioned means comprising a normally compressed expansible

spring convoluted about said mandrel, said spring having one end thereof fixed to said mandrel and the other end of said spring adapted to bear against said adjacent one of said spiders upon expansion of said spring, and a member carried by said mandrel bearing against the free end of said spring for normally retaining the latter in a compressed condition, said member adapt-
ed to be sheared under the expansive action of said spring when said one end of the mandrel is forcibly struck against the bottom of the well, said knives at their free ends being provided with a cutting edge.
15. In a perforating device for well casings, a mandrel adapted for suspension in the well casing, a spider slidably supported on the mandrel adjacent one end of the mandrel, a second spider slidably supported on the mandrel adjacent the other end of said mandrel, vertically disposed arms secured at their ends to the respective spiders for maintaining said spiders in spaced relation on said mandrel, a plurality of cutting knives, means pivotally connecting said cutting knives to the sides of the mandrel intermediate said spiders, trip arms pivoted to said knives and to one of said spiders, said trip arms adapted to be actuated upon sliding movement of said spiders for moving said arms to a cutting position in engagement with the well casing, a collar on one end of said mandrel, a shearable pin extending transversely through the mandrel remote from said collar, a normally partially compressed coiled spring convoluted about said mandrel between said collar and said pin and having one end normally engaging said pin whereby upon the repeated jerking of said mandrel, or repeated forcible engagement of one end of said mandrel with the bottom of the well, said spring will be effective for forcibly shearing said pin whereby upon expansion of the spring subsequent to the shearing of said pin said spring will engage an adjacent one of said spiders for urging both of said spiders relative to said mandrel, and said knives at their free ends being provided with cutting edges, and teeth on the free ends of said knives above said cutting edges.
6. A device for perforating well casings comprising in combination a mandrel, a spider slidable thereon, a collar fixed to said mandrel adjacent one end thereof, a shearable pin extending transversely through the mandrel in spaced relation to said collar, a coiled spring convoluted about said mandrel and normally retained in a partially contracted position between said collar and said pin, a plurality of cutting knives pivoted at one end to the mandrel, means operatively connecting said cutting knives with said spider for effecting swinging movement of the knives upon movement of

said spider relative to said mandrel, and said spring adapted, upon repeated jerking for forcible engagement of the mandrel with a stationary object, to alternately contract and expand for weakening and subsequently shearing said pin whereby upon expansion of said spring one end of the latter will engage said spider for moving the spider relative to said mandrel.

In testimony whereof we affix our signatures.

ARTHUR E. CARTER.
CLARENCE A. JOHNSON.
